CLAIM

The ornamental design for a drywall cart, as shown and described.

DESCRIPTION

This application is being filed contemporaneously with application for U.S. Letters Patent Ser. No. 11/163,330, entitled drywall cart, which is hereby incorporated by reference herein.

FIG. 1 is a perspective view of a drywall cart embodying my design, with the wheel hubs, the caster yokes and attachment plates, the mounting brackets and fasteners associated with the caster attachment plates, and a pair of the removable uprights being shown in broken lines for illustrative purposes only and forming no part of the claimed design;

FIG. 2 is a perspective view of the drywall cart taken from an angle opposite that of FIG. 1;

FIG. 3 is a side elevation view thereof, with the opposite side elevation being a mirror image;

FIG. 4 is an end elevation view thereof, with the opposite end elevation being a mirror image; and,

FIG. 5 is a plan view thereof.
